10 INVENTION
JOHN D. DIXON

JOHN P. DIECKMANN

By *Mundt & Co.*
ATTORNEYS.

UNITED STATES PATENT OFFICE.

JOHN P. DIECKMANN, OF OAKFIELD, WISCONSIN.

BED.

1,372,219.

Specification of Letters Patent.

Patented Mar. 22, 1921.

Application filed June 8, 1920. Serial No. 387,479.

To all whom it may concern:

Be it known that I, JOHN P. DIECKMANN, a citizen of the German Empire, and a resident of Oakfield, in the county of Fond du Lac and State of Wisconsin, have invented a new and Improved Bed, of which the following is a full, clear, and exact description.

This invention relates to improvements in beds, an object of the invention being to provide a bed which will give readily with the weight of an occupant and which will be exceedingly comfortable and yielding in use.

15 A further object is to provide a bed in which the spring and mattress, instead of being supported upon the side bars of a stationary bed-frame, are supported on a frame suspended from a crossbar attached 20 to the head and foot pieces of the stationary bed-frame; and springs are employed in the suspension means so that the mattress and spring and the supporting frame are adapted to sink downwardly with the weight 25 of an occupant.

With these and other objects in view, the invention consists in certain novel features of construction and combinations and arrangements of parts as will be more fully 30 hereinafter described and pointed out in the claims.

Figure 1 is a perspective view of my bed; and

Fig. 2 is a view in transverse section on 35 the line 2—2 of Fig. 1.

My improved bed comprises two frames 1 and 2, the frame 1 being stationary and comprising head and foot-pieces 3 and 4, respectively. The head and foot-pieces 3 and 40 4 are of the same height and have side bars 5 connecting them. The head-piece 3 and the foot-piece 4 are formed preferably of inverted U-shaped rods or standards 6 with transverse bars 7 connecting the parallel 45 leg members thereof. Any preferred arrangement of ornamental bars 13 may be employed in connection with the bars 7.

The frame 2 is shorter and narrower than the frame 1 and is suspended within the 50 frame 1. The frame 2 also comprises head and foot-pieces 8 and 9, respectively, formed of inverted U-shaped rods 6' with cross-bars connecting them, and a rectangular frame 10 is secured to the lower ends of the 55 rods 6'. The rods 6' project through the frame 10 and are secured to the frame by

means of nuts 14 located under the frame around the lower threaded ends of the rods. Cotter pins 14' may be provided through the rods 6' under the nuts 14. The frame 60 10 is adapted to fit rather snugly within the side bars 5 of the frame 1 so that there can be no lateral swinging movement of the frame 2 within the frame 1. Any preferred form of bed spring 11 may be supported by 65 the frame 10, and a mattress 12 may be placed upon the spring 11.

A horizontal bar 15 is positioned adjacent its ends on the upper bar of the head and foot-pieces 3 and 4 and has its ends extending beyond the frame 1. The bar 15 is formed with integral depending enlargements 16 adjacent its ends. These enlargements 16 prevent any longitudinal movement of the bar 15.

75 Hangers 17 are provided at the ends of the bar 15, and links 18 connect the hangers 17 to the ends of coil springs 19. The springs in turn have their other ends secured to a plate 20. The plate 20 is perforated at its center to receive an eyebolt 21, the eye portion of the bolt being on the underside of the plate. A nut 22 is screwed on to the upper end of the bolt 21, and a coil spring 23 is located around the bolt 21 80 between the nut 22 and the plate 20. A cotter pin 22' may be positioned through the bolt 21 to prevent accidental displacement of the nut 22.

85 Another horizontal bar 24 extends through the eye of bolt 21 and at its ends supports the head and foot-pieces of the frame 2, the bar 24 being recessed, as shown at 25, to engage the head and foot-pieces 8 and 9 of the frame 2. At each end of the bar 24 a 90 clevis or similar securing device 25' is located around the bar 24 and member 6' to obviate any danger of the accidental displacement of the bar 24. The bar 24 is also recessed at its center portion, as shown at 95 26, to prevent longitudinal movement of the bar within the eyebolt 21.

100 With this construction the bed is not only cushioned by the ordinary bedsprings 11 but also by the springs 19 and 23 used in the suspension of the frame 2. It is of course, to be understood, that the springs 19 and 23 are strong enough to prevent any very material depression of the frame 2 when an occupant is in the bed, although they do 110 afford a noticeable cushioning means.

Various slight changes and alterations

might be made in the general form of the parts without departing from my invention, and hence, I do not limit myself to the precise details set forth but consider myself at 5 liberty to make such slight changes and alterations as fairly fall within the spirit and scope of the appended claims.

I claim:

1. A bed comprising an outer stationary 10 frame, inverted U-shaped standards at each end thereof, a longitudinal bar supported on the intermediate portion of said standards and extending beyond said standards, depending enlargements on said bar limiting its 15 longitudinal movement, hangers on the ends of said bar, links connecting the hangers with the ends of coil springs, said springs having their other ends located in a metal plate, an eyebolt extending through a centrally disposed opening in said plate with the eye portion of the bolt on the underside of said plate, a nut secured to the end of said bolt, 20 a coil spring around the bolt between the nut and the plate, a longitudinal bar ex-

tending through said eyebolt, an inner frame 25 suspended from said last-mentioned bar, said bar having recesses therein adjacent its ends to accommodate the end members of said inner frame, and said bar having a centrally located recess therein adapted to prevent 30 longitudinal movement of the bar within the eyebolt.

2. The combination with a stationary bed frame and a longitudinal bar supported on the head and foot pieces of said frame, of a 25 suspension bed frame, a longitudinal bar supporting the head and foot pieces of said suspension frame, elastic devices connecting the ends of the first mentioned bar with the intermediate portion of the last mentioned 40 bar, said devices comprising hangers at each end of the first mentioned bar, links secured to the hangers, coil springs secured to the links, a plate secured to the springs, and a spring held eye bolt mounted in the plate 45 and supporting said other bar.

JCHN P. DIECKMANN.
